UNITED STATES PATENT OFFICE

134,115

DESIGN FOR AN ANIMATED AMUSEMENT DEVICE

Maxwell B. Litwin, New York, N. Y.

Application January 22, 1942, Serial No. 105,353

Term of patent 3½ years

To all whom it may concern:

Be it known that I, Maxwell B. Litwin, a citizen of the United States of America and resident of the city of New York, county of Richmond, and State of New York, have invented a new, original, and ornamental Design for Animated Amusement Devices, of which the following is a specification, reference being had to the accompanying drawing, forming part thereof.

In the drawing the figure is a view in perspective of an animated amusement device showing my new design.

I claim:

The ornamental design for an animated amusement device, substantially as shown.

MAXWELL B. LITWIN.
